UNITED STATES PATENT OFFICE.

THOMAS ELLIOTT, OF CINCINNATI, OHIO, ASSIGNOR TO THE CINCINNATI CAR COMPANY, OF WINTON PLACE, OHIO, A CORPORATION OF OHIO.

BUFFER FOR RAILWAY CARS.

Application filed November 12, 1924. Serial No. 749,526.

To all whom it may concern:

Be it known that I, THOMAS ELLIOTT, a citizen of the United States, residing at Cincinnati, in the county of Hamilton and

5 State of Ohio, have invented certain new and useful Improvements in Buffers for Railway Cars, of which the following is a specification, reference being had thereto in to the accompanying drawing.

10 This invention relates to railway cars, particularly of the kind used in city and interurban railway operations.

The essential features of my invention are as follows:

15 (1) A form of buffer for obtaining the maximum of strength with the minimum of weight.

(2) Provision in the buffer for accommodating a coupling-pin hole.

20 (3) The attachment of the buffer to the sills of the car body by means of a special clip therefor.

(4) Vestibule corner posts secured to hanger plates and these plates secured to

25 the knee sills of the body structure, whereby in case of breakage of the posts, as in collisions or accidents, the fragments can be removed, particularly the upper portion of such posts, which usually gives way first

30 under such conditions; and whereby the lower portion of the posts, which is secured to the hanger plate can then be also readily removed, after which operations of removal, new posts can be readily installed, 35 as I have ascertained and determined practically.

The foregoing and other features to be mentioned in the following specification constitute the essentials of my invention.

40 In the accompanying drawings:

Figure 1 is a plan view of so much of a conventional car body as is necessary to illustrate my improvements in connection therewith.

45 Figure 2 is a side elevation of what is illustrated in Figure 1.

Figure 3 is an enlarged plan view of my improved buffer, showing also a part of the hanger plate and a corner post in cross section.

50 Figure 4 is a vertical cross section of the

buffer on the line 4-4 of Figure 3, showing particularly the provision of the coupling pin hole.

Figure 5 is a side elevation of a part of 55 the buffer.

Figure 6 is an enlarged view of the buffer in cross section and an elevation of the main clip and a center sill.

Figure 6^a is a cross sectional view of the 60 main sill to show its channel form.

Figure 7 is a view similar to Fig. 6 showing the knee clip and a knee sill in connection with the buffer.

Figure 7^a is a cross sectional view of the 65 knee sill showing the manner in which it is made up of two angle irons.

Figure 8 is a plan view of a portion of 70 the step plate, knee sill, buffer and hanger plate, with the corner post in horizontal section.

Figure 9 is a side elevation of the parts shown in Figure 8, illustrating the buffer more fully and with a part of the vestibule board added.

75 Figure 10 is a side view of the vestibule corner post in detail.

Referring to the drawings, it is to be observed that the portion of Figure 1 embraced in the right hand half is not of 80 moment so far as the present invention is concerned, but is merely shown incidentally to illustrate the main or center sills 1, the knee sills 2, and the step plate 3. These sills in the portion here referred to, at the 85 left, are in one part of the car floor structure and project beyond under what in practice is the platform. At their outer ends the center sills are equipped with main clips 4 which are riveted to the sills as by rivets 90

5. These clips are shown on an enlarged scale in Figure 6 where it will be seen that they comprise a base portion 4^a, a side flange 4^b, and an end flange 4^c. The flange 95 4^a affords the part through which the rivets 5 are extended; the flange 4^b gives strength and rigidity to the clip; and the flange 4^c affords means for connecting the clips with the buffer through a bolt and nut 7 or other fastening device. The center sills pass on 100 beyond the clips 4 and abut against the central portion of the buffer, as shown at

8 in Figures 1 and 6. The under sides of these sills carry plates 9 secured to the sill by rivets 10 and having flanges 11 which are secured to the lower margin of the buffer by means of bolts and nuts 12 or other suitable fastening devices. Then to the base flange of these sills the lower member of the buffer is secured firmly by bolts and nuts 13 or other fastening means.

10 Thus it will be seen that the central portion of the buffer is tied up strongly to the center or main sills 1, which afford braces or abutments against which the blows received by the buffer are thrust and the buffer made to resist the treatment incident to its position.

Then to further sustain the buffer and complete the structure and scheme of tying up the buffer to the body frame, I provide 20 knee clips 14 which are secured by rivets 15, or other fastening means, to the knee sills 2. These knee clips have base flanges 14^a, side flanges 14^b, and end flanges 14^c to, respectively, afford means for attaching these 25 clips by rivets 16 to the knee sills 2 to constitute braces, and to enable the upper portion of the buffer to be secured as by screw bolts and nuts 17 to the clips.

30 The knee sills 2, which are made up of angle bars 2^a and 2^b held by rivets 2^c, are attached to the lower portions of the buffer by means of the plate 18 secured by rivets 19 to the knee and having flanges 20 to which the lower margin of the buffer is secured by bolts and nuts 21. The lower portion of the buffer is further secured to the knee sills by nuts and bolts 22 as best shown in Figure 7.

40 Thus the buffer is further connected to and supported by the frame structure of the body.

I will now describe the form and construction of the buffer which I generally designate 23. In plan view it is crescent 45 shaped and in cross section it is of serpentine form, as seen from Figures 1, 2 and 6. The buffer is made, preferably, of sheet steel either rolled into the form indicated, or is so fashioned by means of forging or die operations, as may be preferred.

50 Viewing the buffer in Figures 1 and 3 it will be observed that its greatest horizontal dimension is at or near its middle, from which point it narrows thence to its ends. Its greatest strength is therefore in the middle portion where the greatest number of 55 blows and their severity are suffered most. At intervals it is braced by the center sills 1 and the knee sills 2. At its extreme ends it is formed into projections or flanges 23^a, best seen in Figures 2, 3 and 5. These flanges are securely fastened to vestibule hanger plates 24 as seen particularly in Figures 2 and 3. Bolts 25 with their nuts are the preferred means for this purpose. These bolts

extend through vestibule corner posts 26, preferably made of wood and thus anchor the lower portion of these posts to the car structure, directly to the hanger plate and to the buffer. Other bolts 27 secure the lower ends of these posts to the lower portions of the hanger plates 24. The posts extend upwardly and are worked into the roof construction. The vestibule dash board 28 is fastened by rivets or bolts, as indicated at 75 29, to the posts and thus further secure them and add to their strength and rigidity.

The purpose of securing the posts in this manner to the car structure is to facilitate 80 their renewal in case of damage or breakage, which sometimes results from collisions or wrecks. It is found that the posts are usually struck hardest in that portion which is above the floor line of the platform. That 85 part of the posts, therefore, is splintered, bent, or completely broken, while the lower portion being thoroughly protected by the buffer and the hanger plate does not so readily give way. It therefore becomes easy to 90 remove the upper portion of the shattered or broken post, and then when that is done, to remove the lower portion and later to insert a new post in the place occupied by the one destroyed. The very fact that one portion 95 of these posts, the lower portion, is not displaced, and the upper portion is displaced by the collision or wreck, makes it easier to remove these posts, the injured portion first, and then the other, than it would 100 be to remove the entire post should all portions of it be shattered. Such has been the teachings of experience with this structure.

Accordingly, it will now be seen that there is an intimate relation between the buffer, 105 the hanger plate and the posts, and that a useful purpose is accomplished by this relation.

It will further be noted that the hanger plates 24, see Figure 8, overlap the upturned end flanges 30 of the step plate 3 and are carried back behind the step plate and abutted against its rear upturned flange 31 and secured to the knee sill 2 by a series of bolts and nuts 32. The hanger plate is also likewise secured to the flange 30 as shown by the bolts and nuts 33.

In this way the posts and buffer are still further connected with the car structure. And it will be noted from Figure 2 that the 110 knee sill 2, as shown by the dotted lines, passes obliquely across the back of the upturned flange 31 of the step plate 34 to which in practice it is suitably secured as by rivets 35.

115 Referring again to the buffer and vestibule dash board, it will be seen that it has upper and lower flanges 23^b, and that the upper flange is secured to this dash board by a row 120 of rivets 23^c.

Referring again, specifically, to the buffer, it will be seen from Figures 1 and 3 that the middle portion of the middle or intermediate section 23^a of the buffer is extended, formed or bent rearward, as seen at 23^e in Figure 3, to give ample space for forming the coupling pin hole 23^f, as shown in Figures 3 and 4. Thimbles 23^g are fitted to this hole to receive and guide the pin. The space 23^h formed in front of the wall 23^a and between the inner horizontal portions of the structure receives the coupling link through which the pin is to pass.

Thus it will be seen that my improved buffer has a crescent shaped outline so as to taper to small dimensions from the maximum width in the central portion; that it has a serpentine cross section to give it great rigidity and has these provisions for the coupling pin and coupling link. And also that by reason of its upper and lower margins it may be and is firmly secured to the adjacent members of the car structure.

It will be understood that I desire to comprehend within my invention such modifications as may be necessary to adapt it to varying conditions and uses.

Having thus fully described my invention, what I claim as new and desire to secure by Letters Patent of the United States, is:

1. A railway car buffer comprising a bar of sheet metal, serpentine in cross section, whereby a plurality of ribs are produced, and provided with a coupling pin hole extending through the several ribs and having a link recess formed within one of the serpentine bends and intersecting the pin hole.

2. A railway car buffer comprising a bar of sheet metal of crescent form, and serpentine in cross section, and provided with marginal flanges, a coupling pin hole and a link recess.

3. A railway car buffer comprising a bar of sheet metal of crescent form and serpentine in cross section, and having end projections and upper and lower flanges, and also having a coupling pin hole formed in its walls with a coupling link recess formed within one of the serpentine bends, the wall constituting such bend being deflected rearward to form such pocket.

4. A railway car buffer comprising a sheet metal bar having a serpentine cross section, the wall of the inner bend being deflected rearward to form a coupling link recess.

5. A railway car buffer comprising a bar of sheet metal of crescent form, and having end projections, upper and lower flanges and a serpentine cross section, and provided with thimbles constituting a coupling pin hole, and having the wall of the inner fold deflected rearward to form a recess for a coupling link.

6. In a railway car, the combination with a buffer having an end projection, of a

hanger plate and a vestibule corner post, and means to secure together such projection, plate and post, and such post extending a suitable distance above the buffer and the plate to constitute a full post.

7. In a railway car, the combination with a buffer having an end projection, of a hanger plate, a step plate having an end flange, and a vestibule corner post, and means to secure together such projection, hanger plate and post, and other means to secure together the hanger plate and such flange of the step plate, the post extending a suitable distance above such plates to constitute a full post.

8. In a railway car, the combination with a buffer of sheet metal of crescent form and serpentine in cross section, of hanger plates overlapping the ends of the buffer, step plates having each an end flange secured to the respective hanger plates, and a vestibule post fitted within each hanger plate and extending upward to form a full post, means to secure the ends of the buffer, hanger plates and posts together, and other means to secure such step plate, flanges and hanger plates together.

9. In a railway car, the combination with a buffer and a vestibule dash board secured to the buffer, of hanger plates overlapping the ends of the buffer, a step plate having end flanges secured to the hanger plates, vestibule corner posts fitted within the hanger plates and extended upward to form full posts, and means to secure the ends of the buffer, hanger plates and posts together, and other means to secure such vestibule board to said posts.

10. In a railway car, the combination with a buffer, of main sills and knee sills, clips secured to the center sills and to the upper portion of the buffer, such sills being projected into the buffer and having their ends secured to the lower portion of the buffer, and other clips secured to the knee sills and the upper portion of the buffer, such knee sills projecting into the buffer and secured to the lower portion of the buffer.

11. In a railway car, the combination with a buffer having a serpentine cross section, of main sills extending into the interior of the buffer and secured to the lower portion thereof, clips secured to the upper portion of said sills and to the upper part of the buffer, and knee sills projected into the interior of the buffer and secured to the lower portion thereof, and other clips secured to the upper part of such sills and to the upper portion of the buffer.

12. In a railway car, the combination with a buffer having a serpentine cross section, of a sill projected into the interior of the buffer and secured to the lower portion thereof, and a clip composed of a base, a base flange and an end flange, such base

flange being secured to the sill and such end flange secured to the upper portion of the buffer.

13. In a railway car, the combination with
5 a buffer comprising a sheet metal bar of
crescent form and serpentine in cross section,
of center sills and knee sills projecting into
the interior of the buffer and secured thereto
below the lower serpentine bend, and clips
10 secured to the upper surfaces of such sills
and secured to the buffer above the upper
serpentine bend.

14. In a railway car, the combination with
a buffer comprising a sheet metal bar of
15 crescent shape and serpentine in cross section,
and having the inner serpentine bend

deflected to provide a recess for a coupling link, and having also a coupling pin hole, an upper flange and end projections, of center and knee sills projected into the interior 20
of the buffer and secured thereto, clips secured to the sills and to portions of the buffer, hanger plates overlapping the buffer projections, step plates having flanges secured to the hanger plates, and corner vestibule posts fitted to the hanger plates and secured thereto and to the buffer projections, such posts extending above these connections to constitute a full post.

In testimony whereof I affix my signature.

THOMAS ELLIOTT.
